CLAIM

The ornamental design for a rotatable dispenser for babies' diapers and toiletry, as shown and described.

DESCRIPTION

FIG. 1 is a top plan view of a rotatable dispenser for babies' diapers and toiletry showing my new design; FIG. 2 is a front elevational view thereof; FIG. 3 is a side elevational view thereof, the side opposite being substantially a mirror image; FIG. 4 is a bottom plan view thereof; and FIG. 5 is a rear elevational view thereof.
